(57) **CLAIM**

The ornamental design for a mobile phone with rotatable keyboard, as shown and described.

DESCRIPTION

FIG. 1 is a front, side perspective view of a mobile phone with rotatable keyboard showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front view of the mobile phone with the keyboard rotated to an alternate position.
